PORTABLE HEATER

John A. Groves, Hull St., Rochester, Pa.

Filed Nov. 18, 1963, Ser. No. 77,474

Term of patent 7 years

(Cl. D81—20)

FIGURE 1 is a side elevation of a portable heater showing my new design; the opposite side is substantially the same as the side shown except for the fuel line connection assembly as illustrated in FIGURE 3.

FIGURE 2 is a front elevational view thereof; and FIGURE 3 is a rear elevational view thereof.

FIGURE 4 is a reduced top plan view thereof with the heat reflector assembly and mounting means omitted.

I claim:

The ornamental design for a portable heater, as shown and described.
